AUTOMATIC DUST HANDLING SYSTEM

Lauritz E. Mylting, Merchantville, N. J., assignor
to The Allen-Sherman-Hoff Company, Philadelphia, Pa., a corporation of Pennsylvania

Application March 18, 1947, Serial No. 735,474

15 Claims. (Cl. 302—17)

1 This invention relates to the art of handling finely divided solids and more particularly to a new and improved system, method, and apparatus for handling the fine dust which is carried by the gases out of solid fuel burning furnaces.

In large boiler plants the disposal of ash has always been a difficult matter because of the large volume of material to be handled, the character of the material, and the numerous points from which it must be collected. Specifically, in steam generating plants employing solid fuel a powder ash resulting from combustion settles from the gases into hoppers, or is precipitated electrically into hoppers.

One successful system for the disposition of this ash is disclosed in the application of Frank B. Allen, Serial No. 483,275, filed April 16, 1943 for Automatic Dust Removing System, now Patent No. 2,420,217 issued May 6, 1947. In the Allen system, the finely divided ash is drawn off by air flow, induced by an aspirator, through conduits to a centrifugal separator or the like in which the ash is separated from the air. The ash is then mixed with water and dropped into cars or the like for disposition. The ash pipes are connected to the individual hoppers through dust valves which normally remain closed to maintain the vacuum in the system except, of course, the valve corresponding to the particular hopper being emptied. The dust valves, which are immediately below the hoppers, are opened and closed in the Allen system by electromechanical thrust-ers which rotate shafts extending to several valves and operating the valves mechanically in sequence.

The present invention may be regarded in some respects as an improvement of the Allen system, particularly in the means for operating the various valves of the dust handling portion of the system. The hoppers, dust separator, means for disposing of the dust, and vacuum producing device of the Allen system may be used with the system of the present invention. The principal objective of the improved system disclosed herein is to provide a simpler and more flexible control system for the dust valves which will minimize the physical difficulties and expense of installation of the system, provide a more sensitive and responsive control of the operation of the dust valves, provide for selective operation of groups of the dust valves or of certain dust valves only, and require a minimum of maintenance. The invention disclosed herein provides for substantially fully automatic operation of the system. In addition, it provides for the incorporation of

2 segregating valves to isolate inactive sections of the dust conduit and thus minimize air leakage into the system with the consequent reduction of vacuum and loss of efficiency of the system.

5 These objectives are realized in the preferred embodiment of the invention by the provision of a pneumatic actuator for each dust valve and segregating valve, the actuators being controlled by solenoid-operated valves, and by the provision

10 of a novel electrical system for energizing the solenoids in proper sequence to empty the hoppers successively. The electrical system is largely dependent upon a special rotary sequence control switch, the operation of which is monitored by devices responsive to the vacuum in the system to assure that each dust valve is kept open the requisite time to empty the corresponding hopper. As each hopper is emptied, the system will proceed to the emptying of the next selected hopper.

15 20 The nature of the invention, the advantages thereof, and the manner in which the various objectives are realized may be better understood by referring to the description herein of the preferred embodiment of the invention.

25 Referring to the drawings, Fig. 1 is a schematic diagram of a dust handling system in accordance with the invention;

Fig. 2 is an elevation view of an electrically controlled pneumatically operated dust valve;

30 Fig. 3 is a longitudinal section of an automatic materials handling controlled switch;

Fig. 4 is a detail of the same.

Fig. 5 is a partial cross-sectional view taken on the plane indicated by the line 5—5 in Fig. 3;

35 Fig. 6 is a partial cross-sectional view taken on the plane indicated by the line 6—6 in Fig. 3; and

Figs. 7 and 8 taken together constitute a wiring diagram of the system.

General description

40 Referring to Fig. 1, the system is adapted for the removal of dust from a plurality of hoppers 11. A dust valve 12 below each hopper is connected by conduits 13 to one of two segregating valves 15; the segregating valves being connected by a conduit 16 to a dust collector 17 which may be of a well-known type in which the dust is separated centrifugally from the air and falls into a hopper 18. Flow of air through the system is preferably induced by an aspirator 19 actuated by a stream of water under pressure supplied through a conduit 20 and valve 21. The aspirator withdraws air from the system through a line 22 connected to the separator and thus induces 45 a vacuum in the dust handling pipes 13 and 16.

A branch vacuum line 23 runs to the control panel 24 where, as will be seen, the degree of vacuum in the system is employed to monitor the operation of the system.

The parts of the system described thus far may be as more fully described in the abovementioned application of Frank B. Allen, except that the dust valves are adapted for electropneumatic actuation and the segregating valves are added. The dust valves 12 and the segregating valves 15 are provided with pneumatic operators which are supplied through a compressed air line 27. Electric power is supplied to the control panel through a line 28 from which it is distributed through conductors indicated generally at 29 to electrical control devices for the pneumatic valve operators. The nature of the instrumentalities incorporated in the control panel will be made apparent in the description of the operation of the system, taken in connection with the wiring diagram. The specific location of the various devices on or in the control panel is a matter of choice.

A system involving seven hoppers and two segregating valves is described herein. It will be apparent upon further consideration of the system that it is adapted for the operation of as many as 30 dust valves in many groups.

Before proceeding to detailed description of the system, certain of the mechanisms employed therein will be described as an aid to the understanding of the system.

Windswept dust valve

The windswept dust valve preferably employed in the system and illustrated in Fig. 2 is generally similar to that disclosed in U. S. Patent No. 2,368,395 to Frank B. Allen. Electro-pneumatic valve opening means is substituted for the operating shaft employed in the patent. The valve 12 comprises a body formed with a flange 41 by means of which the dust valve is bolted to the bottom of the hopper 11. The ash tends to drop into the receiving portion 42 of the valve. A lateral extension of the body which encloses the valve chamber per se 43 is formed with a flange to which is bolted an outlet connection 44 to which is connected the vacuum line 13 (Fig. 1) through which the ash is exhausted.

The clack valve mounted within the chamber 43 comprises a door 46 normally seating against the inner end of the outlet connection 44 and suspended by a hinge 47 keyed to an operating shaft 48. A pivot pin 49 passes through a clevisled lug 50 adjacent the upper edge of the door and through the central portion of the hinge 47. A second pivot pin 51 fitted in the lower end of the arm 41 passes through a hole 52 in a lug projecting from the center of the door, the hole 52 being sufficiently large to afford a considerable amount of free travel to the pin 51. Normally the door 46 tends to remain closed under the influence of vacuum in the outlet connection, but it may be opened when desired by rotation of the shaft 48, whereupon air is drawn into the valve through a pipe 89 mounted in an adapter 91 and passing below a partition 92 which partially separates the chambers 42 and 43. The ash will be drawn out of the chamber 42 along with the air. A pipe T 93 nipped to the adapter provides for the installation of a low pressure air supply line 94 which may be desirable in applications of the dust valve to precipitator hoppers, or the installation of a check valve (not shown) on a nipple 95. The check valve is installed so as to ad-

mit air to the pipe 89 and chamber 43 when a vacuum exists within the chamber 43.

The mechanism for opening and closing the clack valve 46 comprises the shaft 48 which is journalled in the side walls of the chamber 43 and extends into a crank housing 57 fixed to the dust valve. The crank arm 58 keyed to the shaft 48 is connected to a piston 59 by connecting rod 60. Piston 59 works in a cylinder 61 fitted in a recess in the housing. The cylinder is provided with a head 62. The cylinder, cylinder head, and crank arm housing are supported on a bracket 63 bolted to the body of the dust valve, the bracket being formed with a lateral extension 64 bored to fit around the cylinder 61. Four studs 66 threaded into the housing 57 are fitted with nuts 67 by means of which the cylinder head, cylinder and crank housing are compressively retained in assembled relation. Nuts 68, run up on two of the studs, engage the faces of the bracket 64 to locate and retain the entire assembly on the bracket.

The piston 59 is urged downwardly in the cylinder by a spring 70 received in a seat 71 in the housing 57 and fitted around the skirt 72 of the piston, which is of smaller diameter than the head. A cup leather 73 is retained on the lower face of the piston by a plate 74 and a machine screw 75. The cylinder is formed with a breather hole 76 near the upper end. Compressed air for the actuation of the piston 59 is supplied from the line 27 through a two-way solenoid-operated valve 71. Since valves of the type illustrated here are well-known articles of commerce, the valve will not be described in detail. A solenoid mounted within the cap 78 at the top of the valve operates, through suitable linkage, valves which alternately close off the inlet connection 79 or the vent connection 80, the vent connection being opened when the solenoid is deenergized and the inlet connection 27 being open when the solenoid is energized. The delivery connection 81 is always open. Thus, upon energization of the solenoid, compressed air passes through the open inlet 79, the delivery connection 81, and piping 82 to the inlet 83 in the cylinder head, driving the piston upward. Air compressed above the piston is vented through the opening 76. As the piston ascends it rotates arm 58, shaft 48, and hinge 47 clockwise, drawing the valve door 46 from its seat. To close the valve 46, the solenoid is deenergized, shutting off the supply of compressed air and opening the vent connection 80. The spring 70 is thus able to force the piston down, exhausting the air below the piston through the pipe 82, valve 71, and pipe 85 into the interior of the housing 57.

Segregating valves

The segregating valves 15 (Fig. 1) are not illustrated in detail, since they may be of the same type of construction, insofar as the valve and its operating mechanism are concerned, as the dust valve. The body of the valve will, of course, be simply such as is adapted to mounting in a dust conduit. It may be noted at this point that, insofar as the overall system is concerned, the dust valves and segregating valves may be of any suitable form and the actuator for the valves may be of any suitable type adapted for electrical control. The electrical control is an important feature in realizing the advantages of the invention, but may be employed through various instrumentalities at the valves, such, for example, as 75 individual electric motors.

The automatic material handling control switch

This switch, illustrated in Figs. 3 to 6, is an important element of the invention and has been developed to make possible the realization of the advantages implicit in the conception of the system. This switch effects the sequential actuation of the various elements of the system and is particularly adapted for control of the progress of the operation under the supervisory action of devices responsive to the vacuum in the system. The switch is designed for ready adaptation to ash handling installations of different characteristics by varying the number and form of the cams and installation of various switch combinations.

The control switch 100 is of a motor-driven type, provided with a number of cams mounted on a central shaft for operation of fixed switches to control the dust and segregating valves and provide part of the control for the switch motor. A second camshaft driven at a higher speed also is instrumental in controlling the operation of the motor.

All the parts of the control switch 100 (Fig. 3) are supported by a switch base 101, formed with a generally flat rear face which may be mounted against the front of the control panel 24. A cup-shaped switch frame 102 mounts the fixed switches and supports the camshaft. The frame is formed with a flange 103 extending around most of its open end, which is secured by cap screws 103a (Fig. 6) to the base 101. A pilot 104 (Fig. 3) on the base is received in a counterbore in the frame to insure exact alignment of the two parts. The low speed camshaft 106 is journaled in a bushing 107 in the end of the frame and in a bushing 108 fitted in a cover plate 109 secured to the front of the base plate by machine screws, one of which is identified at 110. The high speed camshaft 111, which is hollow and surrounds the reduced intermediate portion of the camshaft 106, is journaled in a bushing 112 fitted in the base 101 and journaled on a bushing 113 retained between a flange 114 on the slow speed camshaft and a flange 115 at the rear end of the high speed camshaft. The camshafts are restrained against axial movement by the bushing 113, a collar 116 secured to the camshaft 111 by a setscrew and engaging the inner face of the bushing 112, and a collar 117 secured to the camshaft 106 by a setscrew and engaging the inner face of the bushing 107.

The camshafts are driven by a motor 120, preferably of the single-phase capacitor synchronous type, located in the lower part of the enclosure formed by the cover plate 109. The motor is fixed to a mounting plate 121 secured to the base 101 by machine screws, and drives the camshafts through a chain of reduction gearing so designed that the shaft 111 makes 30 revolutions for each revolution of the shaft 106. The gear train comprises a pinion 122 on the motor shaft driving a gear 123 rotatable on a stud 124 extending from the switch base, which in turn drives a gear 126. The gear 126 and a pinion 127 integral therewith are journaled on a headed stud 128 screwed into the base 101. A pinion 129 keyed to the front end of the high speed shaft 111 is driven by the gear 126, and a gear 131 keyed to the slow speed shaft is driven from the pinion 127 through a speed-reducing gear and pinion unit 132 journaled on a stud 133.

The angular position of the camshaft 106 is indicated by an assembly comprising an indicator

wheel 134 clamped on the reduced front end of the shaft by a nut 136. Light from an annular light source 137 mounted on the front of the cover plate 109 passes through an opening 138 in the indicator plate and illuminates a translucent dial 139 fixed in the cover plate. Numbers from one to thirty are equally spaced about the periphery of the dial 139 in position to be designated by the light passing through the opening 138.

Four radial cams 141, 142, 143, and 144 are mounted on the high speed shaft 111 between the flange 115 and a collar 145 screwed onto the shaft. The cams are held against rotation relative to the shaft by a key 146, and the collar by a washer 147 engaged in the keyway and provided with a tab which may be bent down into a groove in the threaded collar. These cams, as will be described later, control the operation of the motor 120 so that it drives the shaft 111 through 180 degrees and the shaft 106 through six degrees at each operation of the motor.

A number of radial cams suited to the particular installation are mounted on the shaft 106. The design illustrated herein is adapted for the fitting of thirteen cams or any lesser number. For purposes of illustration, it may be assumed that cams 151, 152, 153, and 154 actuate boiler selector limit switches, cams 161, 162, 163, and

164 actuate segregating valve operating switches, cams 171 and 172 operate starting and homing switches for the motor, and cam 180 operates the dust valve solenoids. The purposes of these switches, and their timing, will be described later.

The cams are retained on the shaft 106 between the flange 114 and a threaded collar 148 and are located angularly by a key 149. A spacer 155 equal in width to one cam is interposed between the cams 172 and 180 to provide needed clearance. A spacer 156, the length of which is determined by the number of cams mounted on the shaft, is disposed between the cams 164 and 171 to locate cam 180 in its proper position at the end of the shaft.

The cam-operated switches are mounted as follows: The upper portion of the switch frame 102 is of considerable thickness (Figs. 3 and 6), and is milled to provide five longitudinal fins 157 with switch-receiving slots 158 between the fins. The slots are spaced at an angle of twelve degrees with respect to the shafts. The entire periphery of the frame 102 at its rear end circumjacent the cam 180 is of added thickness, and is formed with a total of thirty fins 157 and slots 158, spaced at an angle of twelve degrees. The cam 180 may actuate any number of switches up to thirty, four switches 159 being shown in position in Fig. 5.

All the switches 159 are of similar construction throughout the device except that some are normally open, some are normally closed, and some are double-throw. They are of a type which is well known commercially comprising a rectangular body containing the circuit maker and breaker and having an actuating plunger 166 extending from the body. These plungers extend through holes 167a drilled radially through the frame into position to be actuated by the riser of the corresponding cam, such as cam 180 in Fig. 5. The switches are held in place by machine screws 167 and washers 168 of insulating material bearing against the outer surface of the switches. In the embodiment described herein, cam 180 is the only one which operates more than one switch. The switches operated by the other cams

are mounted in the four slots 158 in the top of the frame 102, the provision of four slots permitting a staggered mounting of the switches to provide the necessary longitudinal clearance. Each cam is formed with a riser such as 170 (Fig. 5) or 173 (Fig. 6), the length of the riser being adapted to the characteristics of the dust handling system and the function the particular cam plays in the system. A terminal and fuse block 174 for the motor (Fig. 6) and a terminal block 175 for the dial light may be mounted on the sides of the frame 102. The leads to the motor and light are led through bushings 176 in the upper portion of the base 101. Leads from the various switches 159 and from the motor and dial light terminal blocks are connected to the circuits external to the switch through an assembly including a switch connector plate 182 (Fig. 3) and a remote connector plate 183. The switch connector plate 182 is secured to the rear end of the frame 102 by studs 184 threaded into bosses 185 extending from the frame. The outer ends of the studs 184 are cylindrical and serve to locate the remote connector plate 183 with respect to the switch connector plate. The leads from within the switch are connected to hexagon headed terminal bolts 186 (Fig. 4) which are retained in the plate 182 by nuts 187 and are provided with second nuts 188 to hold the wire terminals. The external wiring is connected to terminal bolts 189 in the plate 183, held by the nut 190 which secures the terminal in the plate 183 and a second nut 191. A connector strip 192 is retained under the head of the terminal 189 in position to engage the head of the corresponding terminal 186 when the two terminal plates are in juxtaposition. Connector screws 194 passing through holes in the strips 192 are adapted for engagement in tapped holes 195 in the heads of the terminals 186. The heads of the screws 194 are disposed within recessed bores 196 in the plate 183 so that they are prevented from falling out of the plate 183. When the external and internal connections have been made, it is only necessary to slip the plate 183 over the studs 184, which may be so located as to determine uniquely the angular position of the plate 183, and then tighten the screws 184. A switch cover 197, consisting of a cylinder of sheet material or the like, adapted to protect the internal wiring of the switch, is slipped over the plate 182 and against a shoulder 198 on the switch base before the external connection plate 183 is assembled onto the switch.

Miscellaneous apparatus

The system also includes a number of devices principally mounted in the control panel, such as manual switches, relays, indicator lights, a time delay switch, and vacuum operated switches. Since these devices are well known and commercially available, and no claim is made to the specific structure of these elements, they will be mentioned only in connection with the description of the operation of the system.

Electrical circuits and operation of the system

The operation of the system will be described with reference to the schematic diagram of Fig. 1 and the wiring diagram of Figs. 7 and 8. Referring to the wiring diagrams, Fig. 8 shows the automatic sequence control switch 100, and, at the right, the dust valve and segregating valve operating solenoids. Fig. 7 shows all the devices on the control panel except the switch 100. Power for the operation of the system is fed

through conductors 28 to a main power switch 200 which remains closed when closed manually and may, of course, incorporate overload circuit breakers or fuses. The main switch 200 energizes conductors 201 and 202 which may be considered as supply and return conductors for the various units of the system. In tracing circuits herein, unless otherwise specified, they will be traced from the supply conductor 201 to the return conductor 202 and conductors 201 and 202 will not be mentioned, in order to avoid prolixity. In addition to electric power, the system must be supplied with compressed air through line 27 to operate the valves, and with water through pipe 20 to produce the vacuum.

The ash hoppers ordinarily may be divided into groups, and means are provided by which the hoppers of any or all groups may be emptied. The selection of groups is effected by boiler group control units such as 210 and 310, shown set off by dotted lines in Fig. 7.

In order to avoid unnecessary complexity, the wiring diagram shows a system involving only two boiler groups with three dust valves in each group, a seventh dust valve not in either group, and two segregating valves. As will be apparent from the description of the system, it may readily be expanded to handle more and larger groups of dust valves and more segregating valves. The principles of the larger system are the same as those of the small system of which the wiring diagram is shown.

A group control units 210, 310 is installed on the control panel for each boiler group in the system. Since these units are identical only one will be described in detail. When the main contactor 200 is closed and vacuum has been established, assuming the operator wishes to empty the hoppers of boiler group one, he moves group control switch 211 to its "on" position. This switch will remain in either circuit-closing position. When moved to the "on" position the switch 211 completes a circuit through its contacts 212, conductor 213, group control relay coil 214, and conductor 215. The relay opens its back contact 216 extinguishing the "Boiler Group Off," signal light 217. The relay also closes its front contact 219, energizing the "Boiler Group On," indicator light 220. Thus, by the indicator lights 217 and 220 and corresponding indicators in the other group control units, the attendant can readily see which groups have been cut in. Normally, the system is set up for automatic operation by means of the manual-automatic switch 350, the contact member of which may be locked in engagement with its "automatic" contacts 351 to prepare circuits which will be described presently. With the boiler group selection established and the system set up for automatic operation, the operation is initiated by closing the "Start" push button switch 360. This energizes the circuit holding relay 370 by a circuit through the switch contacts 361, wire 362, relay coil 370, wire 363, and switch 271 operated by the cam 171, the switch 271 being closed

when the control switch 100 is in its starting position. Relay 370 closes its front contact 371, shunting the starting switch 360, and thus holding the relay energized, through wires 372, 362, and 363 and switch 271. The "System Energized" indicator light 375 is energized through contact 371 and wires 372 and 373.

At this time none of the dust valves or segregating valves is open, and the first operation performed by the control switch 100 is to open the

group one segregating valve and numer one dust valve. Since the valves should not be opened unless the proper amount of vacuum is present, the operation of the motor 120 to cause opening of any dust valve is under control of a "Vacuum High" switch 380, which is actuated by a pressure responsive device (not shown) connected to the vacuum line 23 (Fig. 1) so as to close its contacts 381 whenever the degree of vacuum in the system is such as normally should obtain with the aspirator 19 in operation and all the dust valves closed. On closing of the vacuum high switch contacts 381, a circuit is closed through wire 382, contact 241, which is held closed by the cam 141 when the control switch 100 is in its starting position, wire 376, a normally closed switch 500, wire 377, front contact 378 of relay 370, and wire 379 to the motor 120. The motor thus begins to operate and drives the cam 180 at low speed, the cam lift moving toward the plunger of the switch 281 controlling the solenoid 291 of dust valve No. 1. The motor also drives cam 161 toward the position in which it operates switch 261 to energize the solenoid 301 of segregating valve number one which controls the flow of material from dust valve number one. Before the solenoids 291 and 301 are energized, the cam 142 on the high speed shaft closes its contact 242. This contact, which closes after 15° rotation of the high speed cam shaft 111 and remains closed until 180° degrees rotation is completed is provided to insure that the motor drives the cam shaft 111 through a full half turn and the cam shaft 106 through six degrees, although the vacuum drops off as the valves are opened. Switch 242 simply shunts the vacuum high switch, providing a circuit through switch 242, wire 376, switch 500, wire 377, contact 378, and wire 379 to the motor. Subsequent to the closing of switch 242, switch 241 opens under rotation of the cam, and after 180° degrees rotation of the cam shaft 111, contact 242 opens, deenergizing the motor.

At this time switch 281 and 261 have been closed to energize valve solenoids 291 and 301. Switch 261 by closing its normally open contact completes a circuit through wires 263 and the solenoid 301 and a circuit through wires 263 and 264 to a "Segregating Valve Number One Open" indicator light 222. At the same time, switch 261 extinguishes a "Segregating Valve Number One Closed" indicator light 223 which is energized through the normally closed contact of switch 261 and wire 265. The indicator lights 222 and 223, and similar indicator lights of the other groups, show at all times the open or closed condition of the segregating valves. The energizing circuit for all the dust valves in group number one is prepared by front contact 224 of group number one control relay 214 whenever that group is selected. The circuit is through contact 224 and wire 225 to the individual switches 281, 282, and 283 which control the group one dust valve solenoids. Thus, when the lift of cam 180 closes the first switch 281, solenoid 291 is energized. With the system in this condition, the ash is drawn from number one hopper through the number one dust valve 12, Fig. 1, pipes 13, segregating valve 15 and pipe 16 into the separator 17. As long as the hopper contains ash which is being transported by the system, a considerable vacuum will be present in the system and in the line 23.

However, when the hopper has been emptied the vacuum will decrease to a low value. In response to this condition, the control switch 100 is energized to close the first dust valve. This

operation is initiated by a "Vacuum Low" switch 390 operated by a pressure responsive device (not shown) coupled to the pipe 23. When the vacuum is broken, the contacts 391 of the switch are closed. However, inasmuch as a temporary low vacuum condition might result from momentary arching of the material in the hopper, a time delay device 400 is installed to prevent closing of the dust valves unless the low vacuum condition persists for a predetermined time. The timer 400 is of a well-known type comprising an electric motor 401 which, through suitable mechanism, closes a normally open contact 402 after a preset period of operation. A desirable time range for this system is from two to thirty seconds, and the timer may be set to any desired delay within this range on a basis of experience in the operation of a particular installation. The vacuum low switch closes the circuit through its contact 391, wire 392, time delay motor 401, wire 393, and a normally closed switch 501. After its preset period of operation, the motor 401 completes a circuit through contact 351 of the manual-automatic switch, wires 352 and 353, contact 402, wire 403, switch 243 closed by the rotary switch cam 143, wire 376, switch 500, wire 377, contact 378, and wire 379 to the motor 120. The contact 243 is closed by the rotary switch shortly before the completion of the first 180° degrees rotation of the cam shaft 111, and remains closed until after switch 244 is closed by the cam 144 at 195° degrees rotation from the starting point. Timer switch 402 and cam switch 243 thus initiate operation of the motor, and switch 244 maintains the motor in operation, regardless of the vacuum condition of the system, until the completion of 360° degrees rotation of the high speed cam shaft. The motor is energized through switch 244, wire 375 and the remainder of the circuit just traced; the switch 244 shunting the manual-automatic switch and timer switch. Switch 244 opens after 360° degrees rotation, at which time switch 241 has been closed, preparing the previously traced circuit through the vacuum high switch for the next cycle of operation.

As the motor rotates the high speed cam shaft through its second half turn the low speed cam shaft is rotated from its 6° degree to its 12° degree position and cam 180 opens switch 281, deenergizing solenoid 291 and causing the closing of the number one dust valve. When the dust valve closes, the vacuum in the system increases and the vacuum high switch initiates operation of the motor to open dust valve number two by the action of cam 180, switch 282, and solenoid 292. The operation thus continues until all the hoppers of group one have been emptied. As the final solenoid 293 of group one is deenergized, completing the emptying of all the hoppers tributary to the number one segregating valve, cam 161 releases switch 261, deenergizing solenoid 301, closing the segregating valve, extinguishing the valve open indicator light 222, and energizing the valve closed light 223.

The segregating valve circuits pass only through the cam-operated switches 261 and 262, and thus the segregating valves are opened in succession as the cam shaft 106 proceeds through its cycle regardless of the setting of the group control units 210, 310 and the like. However, if one group of hoppers is not to be emptied the dust valves of the group will remain closed and there will be no loss of vacuum in the system. Unless means were provided to cause the motor to operate through the positions of the low speed

cam shaft corresponding to that group, the motor would remain deenergized, after completing the first half cycle of rotation of the high speed cam shaft after entering the group. In order to operate the motor through an unselected boiler group the selector switch 211 in its "off" position closes a circuit through its contacts 230, wire 231, boiler group limit switch 251, wire 253, wire 319 and motor 120. The limit switch 251 is held closed by the cam 151 on the low speed shaft during that portion of its rotation which corresponds to the opening of the individual dust valves of group one.

After the completion of group one, the control switch cam 180, as soon as vacuum is restored to the system, is operated to close switch 284 and energize solenoid 294 to open the fourth dust valve. It should be noted that this valve is not a member of either group and the energizing circuit for the solenoid proceeds directly from the supply line 201 through the switch 284. This valve will thus be opened regardless of the position of the group controls. Valve number four illustrates the manner in which a valve may be made independent of the group controls if it is desired that the valve be opened during each ash removing cycle. Assuming that number four hopper is in the pipe grouping of the second segregating valve it is necessary for this valve to open as the dust valve opens. Therefore, at this time switch 262 is operated by cam 162 to energize the solenoid 302 of the second segregating valve through wire 266.

When the number four hopper is emptied, the motor will proceed as before, under the control of the vacuum low and time delay switches to deenergize solenoid 294 and proceed with the energization of solenoids 295, 296, and 297 which actuate the dust valves of group number two. If the group two control switch 311 is in its "on" position, the setup for group two is identical to that for group one, and therefore it is unnecessary to describe the operation. The limit switch 252 completes a circuit to run the motor and cam shaft through group two in case that group is not selected, acting in the same manner as switch 251 of group one. Obviously, additional groups may be taken care of by the system by the utilization of additional cams in the switch 100, which, as illustrated in Fig. 3, is provided with sufficient cams for the operation of four groups. Any desired number of dust valves may be included in each group and the total number of dust valves, with the switch as shown in Fig. 3, may be any number up to 30. The length and position of the lifts of the cams on the low speed shaft must be adapted to operate the segregating valves and the limit switches 251 and 252 during that portion of rotation of the cam shaft in which the dust valves belonging to the particular group are actuated.

When the switch reaches the position corresponding to closing of the last material handling valve, which in the illustrated system with seven valves would be after 84 degrees rotation of the main camshaft, cam 172 closes the homing switch 272, energizing the motor directly through switch 272 and wires 253 and 319 to return the main camshaft to its zero position, at which point the switch 272 is opened by the cam. After switch 272 closes, the normally closed switch 271 is opened by the cam 171, breaking the holding circuit for the relay 370, which drops out. Switch 271 is closed shortly before the low speed camshaft reaches its zero position,

preparing the holding circuit for relay 370 through wire 363. However, the circuit is open at contact 371 of the relay. As the main cam-shaft is returned to its starting position, switch 272 opens, deenergizing the motor and leaving the system in condition to be restarted when desired by actuation of the "Start" push button 360.

In the event of a power failure during the operation of the system, all the valve solenoids will be deenergized and the valves will close. The control switch will remain in whatever position it was in at the time of the power failure. When the supply of power is reestablished, the valves are reopened, but in order to start the motor it will be necessary to operate the "Start" button 360 to reenergize the relay 370. This condition will be indicated by the fact that the indicator light 375 will remain extinguished until the system is restarted. When the "Start" button is operated the system will resume operation and complete its cycle.

If either the vacuum high switch 380 or the vacuum low switch 390 should fail to operate during the cycle the operation of the control switch will be interrupted. In order to restart the control switch the attendant may operate a "Jog" switch 410 which is a normally open two-way push button switch. When the switch button is depressed, it closes contacts 411 which shunt the vacuum high switch 381 through wire 413; and when the "Jog" switch button is pulled, it closes contacts 412 which shunt the time delay switch contact 402 through wires 353 and 414.

In case manual rather than automatic operation of the system is desired, the manual-automatic switch 350 is unlocked, opening the circuit which initiates operation of the motor 120 to close the dust valves at contacts 351. With the switch 351 open the motor 120 will operate automatically only to open a valve. In order to close the valve, the attendant must depress the button 350, closing its "Manual" contacts 355 and thus completing a circuit through wires 356, 414 and 403 to the contact 243 of the control switch through which the motor is energized for the valve-closing portions of the cycle. In manual operation, therefore, the attendant may watch a vacuum gauge installed on the control panel and press the button 350 as the gauge indicates, by loss of vacuum, the emptying of each hopper.

If the operator desires to terminate the operation of the system at any point in the cycle during automatic operation, it is only necessary to put all the group control switches, such as 211 and 311, in the "off" position. In this case, no additional valves will be opened, and the motor will run the control switch back to its starting position, being energized through the limit switches 251 and 252 and the homing switch 272. The operator may also skip certain dust valves in a particular group if he desires by watching the control switch dial which indicates the progress of the operation. Just before the motor reaches the point at which it would operate to open the valve or valves which it is desired to skip, the attendant turns the corresponding group selector switch to the "off" position. The motor will then proceed under the control of the boiler limit switch. As it reaches a position to open the next dust valve which the attendant desires to operate, he may return the group control switch to its "on" position causing the resumption of the operation of the dust valves.

The dial light 137 is energized through a trans-

former 420 supplied from the conductors 201 and 202 so that the dial is illuminated whenever the main contactor 200 is closed.

The type of motor which is considered most suitable for driving the control switch is energized through an external capacitor and resistor, which may be mounted within the upper part of the cover plate 109 (Fig. 3) and which have been omitted from the drawings to simplify the same. Obviously, any self-starting motor having relatively constant speed characteristics may be used to drive the switch.

The switches 500 and 501 (Fig. 7) are provided only in case the system utilizes a dust separator 17 of a type that is provided with a dump gate for discharging the ash. With a collector of this type the vacuum is broken when the dump gates are opened with the result that the motor 120 would be energized by the vacuum low switch and might close a dust valve of a hopper which had not been emptied. To prevent this, switches 500 and 501 are opened by the dump gate control. Whenever the gate is opened, switch 501 opens the circuit of the time delay motor 401, preventing its operation by the vacuum low switch, and switch 500 opens the motor circuit, preventing it from being operated except by the boiler limit switches 251 and 252 and the homing switch 272.

Summary

It will be seen that the system as described provides for the automatic emptying of the ash hoppers of any or all groups. Once the operation is initiated, the mechanism will proceed automatically with the operation and shut itself off when the job is finished. The system performs a sequence of operations under a form of control which assures the completion of each operation, specifically, the emptying of each ash hopper, and which upon completion of each individual operation immediately proceeds with the next succeeding operation. The system is also adapted for non-automatic operation under the supervision of an attendant. It is safeguarded against faulty operation resulting from power failures.

From the practical standpoint the system disclosed herein has many advantages over previously known control systems for ash handling installations. The ash hoppers in boiler stations are often in locations which are relatively inaccessible. With the preferred type of dust valve actuator shown herein, it is only necessary to run a compressed air line and an electrical conduit to each hopper. Thus, shafting for the operation of the dust valves is eliminated. Another advantage of individual actuators for the dust valves is that it is no longer necessary to operate all of a number of dust valves connected to a common opening device in order to empty one hopper.

The actuating cylinders for the valves are simple, substantially trouble-free and easily maintained if necessary. The same is true of the solenoid-operated valves which are tried and proven items used in many applications. The elements of the electrical system, with the exception of the rotary control switch, are readily obtainable articles of commerce which are easily understood and do not require skilled personnel for maintenance, replacement or repair. The rotary control switch is a special unit but is of a particularly fool proof construction and inherently of great reliability.

The control system of the invention was conceived in response to the need for a better solution of the problem of handling material and the embodiment of this system chosen for illustration 5 thereof is an ash handling installation. However, it will be apparent that the system is essentially one for the automatic control of operations in a process which is so constituted as to be responsive to the progress of the operations 10 and thus to allow the needed time for each operation and to carry out the operations in proper sequence without unnecessary delay between operations. Therefore, the control system as such should not be regarded as particularly an ash handling system, since many applications to 15 other processes are within the natural field of the control system. In applications other than that described herein, the circuit through which the operation of the switch motor is initiated 20 may be controlled by any suitable condition which indicates the progress of the operations under control by the switch.

Although the foregoing description is necessarily of a detailed character, in order that the 25 invention may be completely set forth, it is to be understood that the specific terminology is not intended to be restrictive or confining, and that various rearrangements of parts and modifications of detail may be resorted to without departing 30 from the scope or spirit of the invention as herein claimed.

One modification which is contemplated is to locate the solenoid-operated valves for the control of the dust valves and segregating valves 35 at a central point, which may be the control cabinet. This would not necessarily entail any modification in the manner of operation of this system, the only significant difference being in the location of elements of the system. In other 40 words, instead of running wires from the control cabinet to solenoids mounted on the dust and segregating valves, air lines would be run from the control cabinet to the valves.

What is claimed is:

45. 1. A system for handling dust comprising a plurality of dust collecting chambers, a dust receiver, a conduit connecting each collecting chamber with the receiver, means to create a vacuum in the receiver, and a normally closed valve between each collecting chamber and the conduit, whereby upon opening the valve gas and dust may be drawn from the collecting chamber into the conduits and thence into the receiver by vacuum, characterized by means for opening the 50 valves comprising an energizable actuator for each valve, a separate electrically-operated control device for each actuator, and means for selectively energizing the control devices.
2. A system for removing dust from a plurality 55 of dust collecting chambers comprising a dust receiver, a conduit connecting each collecting chamber with the receiver, means to create a vacuum in the receiver, and a normally closed valve between each collecting chamber and the conduit, whereby upon opening the valve gas and dust may be drawn from the collecting chamber into the conduits and thence into the receiver by vacuum characterized by automatic means for sequentially opening the valves comprising a separate energizable actuator for each valve.
60. 3. A system for handling dust comprising a plurality of dust collecting chambers, a dust and gas separating chamber, a conduit connecting each collecting chamber with the separating chamber; means to create a vacuum in the sep- 65
- 70
- 75

arating chamber, and a normally closed valve between each collecting chamber and the conduit, whereby upon opening the valve gas and dust may be drawn from the collecting chamber into the conduits by vacuum, characterized by automatic means for sequentially opening the valves comprising a separate energizable actuator for each valve.

4. A system for handling dust comprising a plurality of dust collecting chambers, a dust receiver, a conduit connecting each collecting chamber with the receiver, means to create a vacuum in the receiver, and a normally closed dust valve between each collecting chamber and the conduit, whereby upon opening the valve gas and dust may be drawn from the collecting chamber into the conduits and thence into the receiver by vacuum, characterized by segregating valves each adapted to isolate certain of the dust valves from the receiver, means for selectively opening the dust valves, and means for opening the segregating valve corresponding to the selected dust valve when the dust valve is opened.

5. A system for handling dust comprising a plurality of dust collecting chambers, a dust and gas separating chamber, a conduit connecting each collecting chamber with the separating chamber, means to create a vacuum in the separating chamber, and a normally closed valve between each collecting chamber and the conduit, whereby upon opening the valve gas and dust may be drawn from the collecting chamber into the conduit by vacuum, characterized by a separate actuator for each valve, and means for progressively energizing the actuators comprising means sensitive to a predetermined vacuum in the conduit to initiate action of the energizing means to cause opening of each valve, and means responsive to a predetermined lesser degree of vacuum to initiate action of the energizing means to cause closing of each valve.

6. A system for handling dust comprising a plurality of dust collecting chambers, a dust and gas separating chamber, a conduit connecting each collecting chamber with the separating chamber, means to create a vacuum in the separating chamber, and a normally closed valve between each collecting chamber and the conduit, whereby upon opening the valve gas and dust may be drawn from the collecting chamber into the conduit by vacuum, characterized by a separate actuator for each valve, and means for progressively energizing the actuators comprising means sensitive to a predetermined vacuum in the conduit to initiate action of the energizing means to cause opening of each valve, and means responsive to continuation for a predetermined interval of a predetermined lesser degree of vacuum to initiate action of the energizing means to cause closing of each valve.

7. A system for handling dust comprising a plurality of dust collecting chambers, a dust and gas separating chamber, a conduit connecting each collecting chamber with the separating chamber, means to create a vacuum in the separating chamber, and a normally closed valve between each collecting chamber and the conduit, whereby upon opening the valve gas and dust may be drawn from the collecting chamber into the conduits by vacuum, characterized by a separate actuator for each valve, means for progressively energizing the actuators, and means for preventing energization of selected actuators.

8. A system for handling dust comprising a plurality of dust collecting chambers, a dust and

gas separating chamber, a conduit connecting each collecting chamber with the separating chamber, means to create a vacuum in the separating chamber, and a normally closed valve between each collecting chamber and the conduit, whereby upon opening the valve gas and dust may be drawn from the collecting chamber into the conduits by vacuum, characterized by a separate actuator for each valve, means for progressively energizing the actuators, means responsive to relatively high vacuum in the separating chamber to initiate operation of the energizing means to open a valve, and means responsive to relatively low vacuum in the separating chamber to initiate operation of the energizing means to close a valve.

9. A system for handling dust comprising a plurality of dust collecting chambers, a dust and gas separating chamber, a conduit connecting each collecting chamber with the separating chamber, means to create a vacuum in the separating chamber, and a normally closed valve between each collecting chamber and the conduit, whereby upon opening the valve gas and dust may be drawn from the collecting chamber into the conduits by vacuum, characterized by a separate actuator for each valve, means for progressively energizing the actuators, means responsive to relatively high vacuum in the separating chamber to initiate operation of the energizing means to open a valve, a settable time-delay device to initiate operation of the energizing means to close a valve, and means responsive to relatively low vacuum in the separating chamber to initiate operation of the time-delay device.

10. A system for handling dust comprising a plurality of dust collecting chambers, a dust receiver to which the dust is transported from the chambers, means for creating a vacuum in the receiver, a number of normally closed segregating valves, conduits connecting the segregating valves to the receiver, a normally closed dust valve communicating with each collecting chamber, conduits connecting the dust valves to the several segregating valves, the dust valves connected to each segregating valve constituting a group, and means for sequentially opening the dust valves of any selected group including means responsive to an empty condition of the collecting chamber for effecting closing of the corresponding dust valve and means responsive to the closing of the dust valve for effecting opening of the next dust valve in the sequence.

11. A system for handling dust comprising a plurality of dust collecting chambers, a dust receiver to which the dust is transported from the chambers, means for creating a vacuum in the receiver, a number of normally closed segregating valves, conduits connecting the segregating valves to the receiver, a normally closed dust valve communicating with each collecting chamber, conduits connecting the dust valves to the several segregating valves, the dust valves connected to each segregating valve constituting a group, means for sequentially opening the dust valves of any selected group including means responsive to an empty condition of the collecting chamber for effecting closing of the corresponding dust valve and means responsive to the closing of the dust valve for effecting opening of the next dust valve in the sequence, and means for maintaining the segregating valve of the group open during the periods of operation of the dust valves of the group.

12. A system for handling dust comprising a

plurality of dust collecting chambers, a dust receiver to which the dust is transported from the chambers, means for creating a vacuum in the receiver, a number of normally closed segregating valves, conduits connecting the segregating valves to the receiver, a normally closed dust valve communicating with each collecting chamber, conduits connecting the dust valves to the several segregating valves, the dust valves connected to each segregating valve constituting a group, means for sequentially opening the segregating valves, and means for sequentially opening the dust valves of any selected group including means responsive to an empty condition of the collecting chamber for effecting closing of the corresponding dust valve and means responsive to the closing of the dust valve for effecting opening of the next dust valve in the sequence.

13. A system for handling dust comprising a plurality of dust collecting chambers, a dust receiver to which the dust is transported from the chambers, means for creating a vacuum in the receiver, a number of normally closed segregating valves, conduits connecting the segregating valves to the receiver, a normally closed dust valve communicating with each collecting chamber, conduits connecting the dust valves to the several segregating valves, the dust valves connected to each segregating valve constituting a group, means for sequentially opening the segregating valves, and means for sequentially opening the dust valves of any selected group including means responsive to the vacuum condition of the receiver for effecting closing of the open dust valve and vacuum-sensitive means responsive to the closing of the dust valve for effecting opening of the next dust valve in the sequence.

14. A system for handling dust comprising a plurality of dust collecting chambers, a dust and gas separating chamber, a passage connecting each collecting chamber with the separating chamber, means to create a vacuum in the separating chamber, and a normally closed valve between each collecting chamber and the passage, whereby upon opening the valve gas and dust may be drawn from the collecting chamber into the passage by vacuum, characterized by a separate actuator for each valve, means for progressively energizing the actuators, means sensitive to a predetermined vacuum in the passage to initiate

action of the energizing means to cause opening of each valve, means for disconnecting the sensitive means immediately after initiating the valve-opening cycle, and means for continuing the cycle to full open valve position independent of the sensitive means.

15. A system for handling dust comprising a plurality of dust collecting chambers, a dust and gas separating chamber, a passage connecting each collecting chamber with the separating chamber, means to create a vacuum in the separating chamber, and a normally closed valve between each collecting chamber and the passage, whereby upon opening the valve gas and dust may be drawn from the collecting chamber into the passage by vacuum, characterized by a separate actuator for each valve, means for progressively energizing the actuators, means sensitive to a predetermined vacuum in the passage to initiate action of the energizing means to cause opening of each valve, means for disconnecting the energizing means immediately after initiating the valve-opening cycle, means for continuing the cycle to full open valve position independent of the energizing means, means for connecting a second sensitive means responsive to a predetermined lesser degree of vacuum to the energizing means just prior to reaching the full open valve position, means for the second sensitive means subsequently to initiate the second part of the energizing means cycle for closing the valve, means for disconnecting the second sensitive means immediately after initiating the valve closing action, and means for continuing the cycle to full closed valve position.
